GUN MECHANISM

Ole Horsrud, Fox River Grove, Ill., assignor to
Sears, Roebuck and Co., Chicago, Ill., a cor-
poration of New York

Application July 4, 1939, Serial No. 282,759

5 Claims. (Cl. 42—43)

This invention relates to firearms and is concerned more particularly with a firearm of the over-under type, i. e., having two barrels, one over the other.

It is an object of my invention to provide an improved cocking mechanism.

It is a further object to provide a firearm of this character in which the breech or frame section is of minimum depth.

A further object is to provide in a firearm a frame section which is of trim appearance and is constructed to enable the firearm to be cocked upon the breaking thereof.

It is another object to provide a firearm of the over-under type which does not require the cocking lever pivot to be below the frame proper and which may be cocked with minimum effort.

It is also an object to provide a firearm of the character referred to affording increased bearing area for the breaking pivot.

Another object is to provide a firearm of the character referred to which does not require the cocking lever pivot to be below the frame proper and which must be cocked before the lower barrel can be unloaded or loaded.

Further objects and advantages of the invention will appear as the description proceeds.

The invention will be better understood upon reference to the following description and accompanying drawings, in which:

Fig. 1 is a fragmentary longitudinal section elevation of a firearm constructed in accordance with one form of the invention, with the weapon uncocked and the barrel section locked.

Fig. 2 is a view similar to Fig. 1 but taken from the opposite side of the firearm and showing the barrel section closed but with the locking bolt retracted to allow the firearm to be broken.

Fig. 3 is a fragmentary plan view showing the extent of turning of the releasing lever to unlock the barrel section, taken substantially as indicated by the line 3—3 in Fig. 2.

Fig. 4 is a view similar to Fig. 1 but with the firearm fully broken so that the extracted and newly inserted shells for the lower barrel may clear the breech frame, the locking bolt and its actuating mechanism having returned to the positions shown in Fig. 1.

Fig. 5 is a view similar to Fig. 1 but with the firearm cocked.

Figs. 6, 7 and 8 are sectional views taken substantially as indicated by the lines 6—6, 7—7 and 8—8, respectively, in Fig. 2.

Fig. 9 is a view of a portion of Fig. 2 but with the fore-end removed and the gun broken, in the process of assembly or dis-assembly.

Fig. 10 is a fragmentary sectional view taken as indicated by the line 10—10 in Fig. 9.

Fig. 11 is a fragmentary sectional view taken as indicated by the line 11—11 in Fig. 10.

Fig. 12 shows a detachable connection between the fore-end and the barrel section.

Referring now more particularly to the drawings, there is shown at 15 a breech or frame section and at 16 a barrel section pivoted together at 17. The frame has a U-shaped forward extension 19 whose bight 20 carries a pivot pin 21 about which a lug 22 depending from the barrel section 16 is hooked. A fore-end 25, preferably U-shaped to match the portion 19 of the frame, may be releasably secured to the barrel section 16 in any suitable manner, as by a spring clip 26 (Fig. 12) mounted on the fore-end and adapted to be connected to and disconnected from the lower barrel, and a lug 27 on said barrel releasably received in an opening or slot 28 in the fore-end. The frame affords a bearing surface 29 co-axial with the pivot pin 21, and the fore-end 25 has a cooperating bearing surface 30.

Pivotedly mounted at 31 on the frame 15 is a top or releasing lever 32 urged by a spring 33, by engagement of an end 34 thereof in a notch 35 of said lever, into preferably longitudinal alignment with the firearm but swingable until said spring 20 end contacts the wall 36 (Fig. 8). A releasing link 37 is pivoted as at 38 in an upstanding recess 39 (Fig. 2) in the frame and has its upper end 40 disposed in a recess 41 in the lever 32. The lower end 43 of the link 37 is received in a notch 44 in a locking bolt 46 which is shown as U-shaped (Fig. 7) to provide clearance for another part of the mechanism as will appear. The bolt 46 is longitudinally slidable in the frame 15 and normally projects in advance of the face or standing breech 48 of the frame, which face is adapted to abut the rear face 49 of the barrel section 16. The bolt 46 terminates forwardly in a cam nose 50 adapted to be received in a recess 51 in the rear lower portion of the barrel section.

Assuming the gun has been fired and it is desired to cock it, the lever 32 is turned counterclockwise, looking at the top of the mechanism shown in Fig. 3, moving the upper end 40 of the link 37 forward and consequently the lower end 45 43 of the link backward, retracting the locking bolt 46 and pulling the nose 50 thereof out of the barrel section recess 51. This action also results in withdrawal of the firing pins from the primers of the shells (not shown), as will appear, whereupon the firearm may be broken. When the firearm is slightly broken, so that the primers of the shells are raised above the places at which the firing pins struck, and the locking bolt is out of the recess 51, the thumb pressure on the lever 55 32 may be withdrawn since the forward projection of the locking bolt and firing pins at such time will not interfere with the barrel section 16 and the shells in the continued breaking movement.

Reciprocably mounted in the frame 15 is a pair

of firing hammers 54 and 55 terminating forwardly in reduced firing pins 56 adapted to be thrust into the primers of the shells (not shown) carried by the barrels 57 and 58 (Fig. 1). The hammers may be stopped in their forward motion by means to be described. The hammers 54 and 55 are supported rearwardly in a bracket 61, suitably secured to the upper and lower tangs 62 and 63 of the breech frame, and are urged forwardly by firing springs 64 which rearwardly abut collars 65 about the hammers and forwardly abut lugs 67 integral with or rigidly mounted on the respective hammers. The lugs 67 are urged into engagement with the rear upstanding arm 70 of a cocking lever 71 which may be of the first class, fulcrumed at 72 to the bottom plate 73 of the frame 15, the aforementioned bight 20 constituting a forward extension of the plate 73. The arm 70 is illustrated as a fork straddling the hammer 55 but could be a single prong or of any other desired form. The link 37 has a lug 75 which is adapted to seat in a recess 76 so that the link may be flush with the rear upstanding breech wall 77 when the end 43 of the link is in its forwardmost position. The lug 75 is engageable with the arm 70 of the cocking lever 71 when the top lever 32 is turned as explained above, forcing the cocking lever to turn counterclockwise as viewed in Fig. 2. The lever arm 70 during such movement retracts the lugs 67, at the same time that the lower end 43 of the link 37 retracts the locking bolt 46, until the firing pins 56 and the locking bolt nose 50 are flush with or back of the breech frame face 48, whereupon the weapon may be broken about the pivot 17. Pressure on the lever 32 may be released before the cocking is completed, as is evident from the foregoing. It is thus apparent that although the springs 64 are of proper strength to fire the weapon, they need be stressed only a slight amount to permit release of the pins 56. The pressure of the spring 33 on the release lever 32 is likewise small but sufficient, so that only a light, nominal effort is needed to turn the lever 32 sufficiently to withdraw the locking bolt 46 and firing pins 56 to the extent necessary to permit the weapon to be broken. It will be observed that this effort is spread over a substantial angle of turn of the release lever 32, so that the force and energy required are indeed small.

The lug 22 on the barrel section may have a longitudinal slot 80 (Figs. 9, 10 and 11) affording spaced walls 81 providing spaced guideways or tracks 82 in which is slidably a cocking pin 83. A spring 85 anchored at 86 to the lug 22 and at 87 to the pin 83 urges the pin forwardly for a purpose which will appear.

The bottom plate 73 of the frame 15 preferably has its lower face 89 flush with the lower face 90 of the fore-end when the firearm is closed (Figs. 1, 2 and 5), and has a slot 92 in which the fulcrumed portion of the lever 71 is received. The locking recess 51 is formed in a lug 93 divided therebelow at 95 to straddle the forwardly extending actuating arm 96 of the cocking lever 71 and to project down into an enlarged opening 97 at the forward end of the slot 92 and lie preferably flush with the bottom surface 89. The bottom of the opening 97 is preferably substantially filled by the arms of the lug 93 and the adjacent portion 98 of the lever arm 96 when the weapon is unbroken, as is apparent from Fig. 1. The frame bottom is slotted at 100 to accommodate the lever arm 96, and the end 101 of said arm is adapted to lie between the rear end 103 of the

cocking pin 83 and the barrel 58 at all times, while the gun is assembled as is apparent from Figs. 1 and 4.

It will be observed from Fig. 11 that the cocking pin 83 has a longitudinal slot 105 in which a screw 106 in the lug 22 projects to limit the forward and rearward movement of the pin. As has been stated the spring 85 urges the pin 83 forwardly. It will be observed, however, that as the fore-end 25 is moved rearwardly into its operative position on the barrel section 16, its bearing surface 30 engages the forward end of the pin 83, which at the beginning of such movement is relatively disposed as shown in Figs. 9 and 11, and moves the same to its substantially rearmost, i. e., operative, position against the action of the spring 85, as shown in Fig. 1. Now when it is desired to cock the gun, the firing pins 56 and locking bolt 46 are first withdrawn in response to a light pressure of the thumb on the lever 32, and the weapon is broken about the pivot 17. During the breaking action, the cocking pin 83 swings about the pivot 17 as a unit with the barrel section and fore-end 25, the rear end 103 of the pin engaging the under side 107 of the cocking lever arm 96 and sliding forwardly therealong as it rotates the cocking lever 71 clockwise about its fulcrum 72, as is apparent upon inspection of Fig. 4. At the same time, the extractor 107a is moved rearward from the barrel section in a conventional manner.

As the cocking lever 71 swings as aforesaid, its arm 70, acting against the lugs 67 and springs 64, forces the hammers 54 and 55 rearward until the shoulders 108 of the notches 109 in the rear ends 110 of the hammers pass rearwardly beyond the sear ends 111, the sears being pivotally mounted as at 112 on the bracket 61 and pressed by springs 113, as shown in Fig. 4. The springs, acting through the sears, also press the triggers down. The breaking of the firearm is limited by engagement of the rear end 114 of the fore-end 25 with the bight 20 of the breech frame 15. The breaking is stopped with the pin 83 still engaged with the cocking lever arm 96, so that it is impossible to accidentally overswing the barrel section when the firearm is assembled. It will be observed from Fig. 4 that the hammers 54 and 55 are thrust back slightly farther than is necessary to effect their locking in cocked position by the sears 111. Unless the firearm is substantially fully broken, there may be insufficient clearance for ejection and insertion of shells from and into the lower barrel 58. Thus is insured the cocking of the weapon before the lower barrel 58 can be unloaded or loaded.

The barrels are then loaded, whereupon the barrel section 16 is swung clockwise, the rear, preferably inclined face 115 of the lug 93 striking the nose 50 of the locking bolt 46 and camming the same rearwardly against the action of spring 33. When the closing of the fire arm is completed (Fig. 5), the spring 33 snaps the nose 50 of the locking bolt 46 into the recess 51, locking the barrel section in place for firing. When the closing of the firearm is commenced, the cocking lever 71 is free and the same moves counterclockwise by engagement of the upper part of the end 101 thereof by the bottom wall 117 of the barrel section until finally the cocking lever occupies substantially the position shown in Fig. 5. Thereupon the weapon may be fired, the retraction of the upper and lower sears being effected respectively by the triggers 120 and 121, pivoted at 122 to the lower tang 63. A piece

123 may separate the triggers. Any suitable safety means shown generally at 125 may be employed to prevent accidental operation of the triggers. A conventional or other suitable guard 127 may be provided for the triggers.

When either or both triggers are pulled, the lug or lugs 67 fly forward, striking the cocking lever arm 70 which in turn abuts the wall 77 of the breach frame and thus stops the firing hammers as shown in Fig. 1.

The purpose of the spring 85 is to move the cocking pin 83 forward sufficiently to clear the cocking lever 71 when the fore-end 25 is removed from the barrel section, as by springing the clip 26 (Fig. 12), off the barrel 58, whereupon, after the release lever 32 is moved to retract the firing pins and locking bolt sufficiently to enable the remainder of the firearm to be broken, the remainder of the firearm may be broken as seen in Fig. 9, enabling the lug 22 to be freed from the pivot pin 21 so that the barrel section 16 may be completely separated from the breach frame 15. By a reversal of this procedure, the parts of the gun may be reassembled, so that, when the fore-end 25 is in position, it holds the cocking pin 83 in a position where it projects under the cocking lever arm 96 as is evident from Fig. 1.

It will be observed that the cocking arrangement is such as to afford the application of a large torque to the cocking lever 71, with a minimum of exertion on the part of the operator in breaking the firearm. This is possible by virtue of the fact that the actuating force exerted upon the cocking lever by the cocking pin 83 is applied at the forward extremity of the cocking lever arm 96. The other arm 70 of the cocking lever applies its cocking force to the lugs 67 at a relatively short distance from the cocking lever fulcrum 72, so that there is a force multiplication enabling the operator with relative ease to force back the lugs 67 to cock positions against the resistance of the firing springs 64.

The firing springs are preferably not of the rebound type, so that relatively less energy need be expended to overcome their initial resistance to the initial retracting movement of the firing pins to permit breaking. Also, because of the nature of the springs, less force is required to cock the weapon.

Various changes coming within the spirit of my invention may suggest themselves to those skilled in the art and, hence, I do not wish to be restricted to the specific form shown or uses mentioned.

I claim:

1. A firearm comprising a barrel section including a pair of barrels arranged one over the other, a breech section hinged to said barrel section, firing pins in said breech section and disposed to fire shells in said barrels, springs constantly urging said pins toward said barrels, cocking means for said pins, said means comprising a cocking lever having a forked arm straddling the lower pin, the prongs of said arm being engageable with both of said pins, actuating means engageable with said lever to cock the firearm during breaking, a fore-end detachably carried by said barrel section and operative to maintain the hinged relation between said sections and engageable with said actuating means to maintain said actuating means in engagement with said

lever, and yieldable means urging said actuating means to separate from said lever and operative to automatically effect such separation when said fore-end is detached.

- 5 2. A firearm comprising a barrel section including a pair of barrels arranged one over the other, a breech section hinged to said barrel section, firing pins in said breech section and disposed to fire shells in said barrels, springs constantly urging said pins toward said barrels, cocking means for said pins, said means comprising a member engageable with both of said pins for moving them rearwardly, and means for locking and unlocking said sections and operative through said member during unlocking movement to retract said pins to allow the firearm to be broken, said cocking means being operative independently of said locking and unlocking means.
- 10 3. A firearm comprising a barrel section, a breech section hinged to said barrel section, a firing pin in said breech section and disposed to fire a shell in said barrel section, a spring constantly urging said pin toward said barrel section, cocking means for said pin, said means comprising a member engageable with said pin for moving it rearwardly, means for locking and unlocking said sections and operative through said member during unlocking movement to retract said pin to allow said firearm to be broken, said member being engageable directly with and between said breech section and pin when the pin fires, so that the thrust is borne by said breech section.
- 15 4. A firearm comprising a barrel section including a pair of barrels arranged one over the other, a breech section hinged to said barrel section, firing pins in said breech section and disposed to fire shells in said barrels, springs constantly urging said pins toward said barrels, cocking means for said pins, said means comprising an intermediately pivoted cocking lever having a forked arm straddling the lower pin, the prongs of said arm being engageable with both of said pins, actuating means engageable with the other arm of said lever to cock the firearm during breaking, a fore-end detachably carried by said barrel section and operative to maintain the hinged relation between said sections and engageable with said actuating means to maintain said actuating means in engagement with said lever, and yieldable means urging said actuating means to separate from said lever and operative to automatically effect such separation when said fore-end is detached.
- 20 5. A firearm comprising a barrel section including a pair of barrels arranged one over the other, a breech section hinged to said barrel section, firing pins in said breech section and disposed to fire shells in said barrels, springs constantly urging said pins toward said barrels, cocking means for said pins, said means comprising a member engageable with said pins for moving them rearwardly, means for locking and unlocking said sections and operative through said member during unlocking movement to retract said pins to allow the firearm to be broken, said member being engageable directly between and with said breech section and both pins when the pins fire, so that the thrust is borne by said breech section.
- 25 6. A firearm comprising a barrel section including a pair of barrels arranged one over the other, a breech section hinged to said barrel section, firing pins in said breech section and disposed to fire shells in said barrels, springs constantly urging said pins toward said barrels, cocking means for said pins, said means comprising a member engageable with said pins for moving them rearwardly, means for locking and unlocking said sections and operative through said member during unlocking movement to retract said pins to allow the firearm to be broken, said member being engageable directly with and between said breech section and pin when the pin fires, so that the thrust is borne by said breech section.
- 30 7. A firearm comprising a barrel section including a pair of barrels arranged one over the other, a breech section hinged to said barrel section, firing pins in said breech section and disposed to fire shells in said barrels, springs constantly urging said pins toward said barrels, cocking means for said pins, said means comprising a member engageable with said pins for moving them rearwardly, means for locking and unlocking said sections and operative through said member during unlocking movement to retract said pins to allow the firearm to be broken, said member being engageable directly with and between said breech section and pin when the pin fires, so that the thrust is borne by said breech section.
- 35 8. A firearm comprising a barrel section including a pair of barrels arranged one over the other, a breech section hinged to said barrel section, firing pins in said breech section and disposed to fire shells in said barrels, springs constantly urging said pins toward said barrels, cocking means for said pins, said means comprising a member engageable with said pins for moving them rearwardly, means for locking and unlocking said sections and operative through said member during unlocking movement to retract said pins to allow the firearm to be broken, said member being engageable directly with and between said breech section and pin when the pin fires, so that the thrust is borne by said breech section.
- 40 9. A firearm comprising a barrel section including a pair of barrels arranged one over the other, a breech section hinged to said barrel section, firing pins in said breech section and disposed to fire shells in said barrels, springs constantly urging said pins toward said barrels, cocking means for said pins, said means comprising a member engageable with said pins for moving them rearwardly, means for locking and unlocking said sections and operative through said member during unlocking movement to retract said pins to allow the firearm to be broken, said member being engageable directly with and between said breech section and pin when the pin fires, so that the thrust is borne by said breech section.
- 45 10. A firearm comprising a barrel section including a pair of barrels arranged one over the other, a breech section hinged to said barrel section, firing pins in said breech section and disposed to fire shells in said barrels, springs constantly urging said pins toward said barrels, cocking means for said pins, said means comprising a member engageable with said pins for moving them rearwardly, means for locking and unlocking said sections and operative through said member during unlocking movement to retract said pins to allow the firearm to be broken, said member being engageable directly with and between said breech section and pin when the pin fires, so that the thrust is borne by said breech section.
- 50 11. A firearm comprising a barrel section including a pair of barrels arranged one over the other, a breech section hinged to said barrel section, firing pins in said breech section and disposed to fire shells in said barrels, springs constantly urging said pins toward said barrels, cocking means for said pins, said means comprising a member engageable with said pins for moving them rearwardly, means for locking and unlocking said sections and operative through said member during unlocking movement to retract said pins to allow the firearm to be broken, said member being engageable directly with and between said breech section and pin when the pin fires, so that the thrust is borne by said breech section.
- 55 12. A firearm comprising a barrel section including a pair of barrels arranged one over the other, a breech section hinged to said barrel section, firing pins in said breech section and disposed to fire shells in said barrels, springs constantly urging said pins toward said barrels, cocking means for said pins, said means comprising a member engageable with said pins for moving them rearwardly, means for locking and unlocking said sections and operative through said member during unlocking movement to retract said pins to allow the firearm to be broken, said member being engageable directly with and between said breech section and pin when the pin fires, so that the thrust is borne by said breech section.
- 60 13. A firearm comprising a barrel section including a pair of barrels arranged one over the other, a breech section hinged to said barrel section, firing pins in said breech section and disposed to fire shells in said barrels, springs constantly urging said pins toward said barrels, cocking means for said pins, said means comprising a member engageable with said pins for moving them rearwardly, means for locking and unlocking said sections and operative through said member during unlocking movement to retract said pins to allow the firearm to be broken, said member being engageable directly with and between said breech section and pin when the pin fires, so that the thrust is borne by said breech section.
- 65 14. A firearm comprising a barrel section including a pair of barrels arranged one over the other, a breech section hinged to said barrel section, firing pins in said breech section and disposed to fire shells in said barrels, springs constantly urging said pins toward said barrels, cocking means for said pins, said means comprising a member engageable with said pins for moving them rearwardly, means for locking and unlocking said sections and operative through said member during unlocking movement to retract said pins to allow the firearm to be broken, said member being engageable directly with and between said breech section and pin when the pin fires, so that the thrust is borne by said breech section.
- 70 15. A firearm comprising a barrel section including a pair of barrels arranged one over the other, a breech section hinged to said barrel section, firing pins in said breech section and disposed to fire shells in said barrels, springs constantly urging said pins toward said barrels, cocking means for said pins, said means comprising a member engageable with said pins for moving them rearwardly, means for locking and unlocking said sections and operative through said member during unlocking movement to retract said pins to allow the firearm to be broken, said member being engageable directly with and between said breech section and pin when the pin fires, so that the thrust is borne by said breech section.

OLE HORSRUD.
